UNITED STATES PATENT OFFICE

JOSEPH CHIEROTTI, OF LOS ANGELES, CALIFORNIA

BELT AND BUCKLE

Application filed August 13, 1932. Serial No. 628,704.

This invention relates to buckles and connectors for belts and the like and has for an object to provide a buckle of the class whereby there is provided an inside lap of the free 5 end of the belt.

More particularly it is an object to provide an inside lap belt buckle characterized by having a smooth interior surface or face arrangement of parts to avoid objectionable 10 shoulders and projections commonly found in various belt buckles or hitches and leading to common objections, because of unevenness when the belt and buckle are closed around the waist.

Further an object is to provide belt fastening buckle of few, simple, practicable, and substantial parts involving only one principal moving member and this being of the type 15 of a lever of the first order.

An additional object of the invention is to provide a substantial, effective, durable, easily applied and readily disconnected means 20 for hitching a strap end to a master buckle, with the purpose of facilitating the removal 25 of the old or mutilated belt from the master buckle plate at will and providing for the application of a new belt.

While reference has been made hereabove 30 to belts and buckles it is understood that the improvements are not limited to only such adaptations.

The invention consists in certain advancements in this art as set forth in the ensuing 35 disclosure and having, with the above, additional objects and advantages as hereinafter developed, and whose construction, combination and details of means, and the manner of operation will be made manifest in the description of the herewith illustrative embodiment; it being understood that modifications, 40 variations and adaptations may be resorted to within the scope, principle and spirit of the invention as it is more directly claimed hereinafter.

Figure 1 is a top plan of the lapped ends of the belt secured to the buckle.

Figure 2 is an inside face view of the belt ends and buckle.

Figure 3 is a plan or top edge view partly in

section of one form of a laminated belt structure with the keeper partly therethrough.

Figure 4 is a perspective of the separate, master plate of the buckle with its applied 55 latch leaf.

Figure 5 is a perspective of the separated latch leaf showing its inside structural parts.

Figure 6 is a perspective of the separated 60 detachable hitch member of the strap connector.

Figure 7 is a perspective of the coordinate end of the attachable belt.

Figure 8 is a perspective of a free end portion of a belt of a modified form of a latched keeper.

The buckle comprises the main or master front plate 2 having inwardly turned top and bottom flanges 3 and 4 which are provided with inwardly bent coplanar lips 5 forming 70 back channels of guides along the back of the plate 2.

One end of each of the lips 5 is rolled inwardly at 6 to form bearings for a pivot bar 7 fixed on an inner face of latch leaf 8 from the top and bottom edges of which the pivot 75 bar 7 projects to enter the bearing 6.

The leaf forms therefore a lever of the first order one end 8^a of which forms a handle or pressure part while the opposite end portion is provided with a suitable number of prongs 80 or pins 9, which may be pressed inwardly that is toward plate 2 by a suitably disposed spring 10.

The latch prongs 9 are adapted to automatically snap into perforations 12 or eyelets 85 13 which are in the free or slip end 14^a of a belt strap 14.

Preferably the belt 14 is of two or more layers as shown in Figure 3 and the keeper 90 apertures or eyelets extend only through the inner layer so that as seen from outside of front of the belt 14 Figure 3 there are no perforations or other parts visible.

In the form of a belt in Figure 8 by using 95 apertures made in the leather to receive the prongs 9 the leather is reinforced by a cross bar 15 riveted or otherwise secured to the near layer of the leather on the side of the holes 12 subjected to the pull of the inserted prongs 9 of the latch leaf.

When the free end 14^a of the belt is inserted under the yieldable latch leaf this then moves back from the front plate 2, and as the belt end slides past the prongs 9 these will snap into the perforations under the closing action of the spring 10 and securely latch the belt end. Preferably the tips of the latch prongs 9 incline back toward the latch plate 8 in the direction from which the slip end of the belt 10 is inserted to facilitate entry of the belt and pass the prongs.

A feature of the invention comprises a simple, practical means for connecting the belt 14 at one end firmly to the buckle plate 2 and 15 as here shown a hitch member is in the form of a sheet metal stamping 20 of a width from top to bottom equal to the width of the belt 14. Intermediately of one edge, the plate is provided with a depression or embossment 21 20 of width, depth, and length to pass under the complementary hook 22 fixed on the inner face of the buckle plate 2. The hitch member 20 is provided on the same edge as the embossment 21, with a pair of stiff lugs 23, 25 while the opposite portion of the member 20 is formed as a panel 24 forming a guide for the insertion of the lip end 14^a of the belt 14. That end of the belt 14 which is to be hitched to the master buckle plate 2 30 is provided with tongues 25 providing interspace or indenture 26 for clearance of the hitched embossment 21. Also the hitch end of the belt is provided with perforations 27 to receive the detachable lugs 23 of the removable member 20. From the above it will be seen that when it is desired to remove a worn belt it is only necessary to firmly press the belt end into back chamber of the plate 2 to disconnect the embossment 21 35 of the plate 2 from the hook 22 of the plate 2 and then pull the strap and plate together from the buckle. After which the hitch member 20 can be readily unhooked from the perforations 27 of the belt and applied to a new belt having a complementary hitch end, as clearly shown in Figure 7. With the leaf in its normal position as in Fig. 4, the prongs 9 are in latching position to engage in belt holes 12 and are held so by the finger spring 40 10 which is secured flat against the back of the leaf and projects far enough beyond an edge of the leaf to always be in hooking engagement with and in rear of a nearby flange lip 5. If pressure is applied to the leaf end 45 8^a the prongs 9 are drawn outward by outward swing on the leaf end 8 against the resistance of the finger spring lapping under and against the lip 5. Thus the spring acts to pull the leaf back to the plane of the lips 5—5 and to thrust the prongs 9 into the strap 50 holes 12.

The invention claimed is:

1. A buckle having a frontal plate, with top and bottom flanges turned back and having 55 coplanar lips to form a guide channel for a

free strap end insertable at rear of the plate, and a latch leaf pivoted in the plate and having a prong device to engage keeper means on said belt end; said leaf lying in the plane of the lips while engaging said strap end; the leaf being a lever of the first order on one end of which is provided said prong device and the opposite end of which forms a depressible lever.

2. A buckle having a plate with top and bottom flanges having coplanar lips to form a strap end guide channel, and a latch leaf pivoted on the plate and having a prong device to interlock the strap end; the leaf being a lever of the first order lying in the plane of said lips and on one end of which said prong device is provided and the opposite end of which forms an inwardly pressible lever, and spring means normally pressing the leaf to a position flush with the lips and with the prong device in strap engaging position.

3. A detachable buckle and belt connector, comprising a buckle plate having on its back a fixed hook facing inwardly from one end, a strap having near one end a transverse set of perforations and therebetween an indenture to the end edge, and a separable hitch plate having means to hook into said perforations and provided with a portion to slidably and detachably interlock under the said plate hook and lying in said indenture.
